UNITED STATES PATENT OFFICE.

CHARLES ZERGA, OF PHILADELPHIA, PENNSYLVANIA.

SHOE SHANK.

Application filed October 9, 1922, Serial No. 593,230. Renewed September 9, 1926.

My invention relates to new and useful improvements in a shoe shank, and has for its object to provide an exceedingly simple and effective device of this character for attachment to or connection with the arch pad of a shoe that when in use will support the inner arch of the wearer's foot.

Another object of my invention is to provide a shank of this character produced from suitable stiff material, such as metal, that will combine a support with the standard shank to assist in retaining the shape of the shoe and at the same time support the foot of the wearer.

15 A further object of the invention is to construct a shank wing that acts as a support for use by itself or in conjunction with the shank body, said shank wing being formed as a receptacle member or as an integral part 20 of the shank body.

A still further object of the invention is to provide a shoe shank having one or more shank wings in order that either or both sides of the arch of the wearer's foot may be 25 supported.

With these ends in view, this invention consists in the details of construction and combination of elements hereinafter set forth and then specifically designated by the 30 claims.

In order that those skilled in the art to which this invention appertains, may understand how to make and use the same, I will describe its construction in detail, referring 35 by numerals to the accompanying drawings forming a part of this application, in which:—

Fig. 1 is a bottom plan view of a shoe with a portion of the sole broken away to illustrate the application of my improved shoe shank.

Fig. 2 is a section at the line 2—2 of Fig. 1.

Fig. 3 is a plan view of the shoe shank 45 separated from the shoe.

Fig. 4 is an edge view thereof.

Fig. 5 is a view similar to Fig. 3 of a slightly modified form of the device.

Fig. 6 is a plan view of a different 50 formation.

Fig. 7 is also a plan view of another formation.

Fig. 8 is a view similar to Fig. 7, showing the device applied to an arch pad.

55 Fig. 9 is an edge view of Fig. 8.

Fig. 10 is a perspective view of a further modification.

In carrying out my invention as embodied in Figs. 1 to 4 inclusive, 2 represents the upper of a shoe, 3 the insole thereof which when secured to the upper produces the welt 4 between which in the region of the arch is located a pad 5 but which in some cases is omitted. To these parts is joined in the regular well known manner the shoe sole 6.

In the region of the shoe arch is located the shank body 7 which runs substantially lengthwise of the shoe and with this body is formed the shank wing 8 preferably having a reduced neck portion 9 between it and the body. The shank wing conforms to the general contour of the inner arch portion of the shoe and is slightly arcuate in shape, as shown in Fig. 4, in order to produce the proper resiliency and if found desirable each end of the wing may be bent outward 70 to form prongs 10 which are adapted to embed themselves in the leather outer sole when the latter is placed in position prior to securement to the other parts.

Where the device is to be used by a very heavy person the shank body and its wing are made in shorter dimensions as well as much wider, as shown in Fig. 5, and if found desirable the prongs 10 may be eliminated. This latter construction will more readily support the weight of a stout person and better retain the shoe in its proper shape.

In Fig. 6, the shank body 11 has two shank 90 wings 12, one projecting from each side edge of the shank body and connected therewith by means of the necks 13 while the ends of said shank wings are provided with the prongs 14. This construction is provided in 95 order that both sides of the arch of the wearer's foot may be supported if such is desired.

In all of the foregoing constructions the neck of the shank wings is joined to the body 100 adjacent one end although never at the extremity of the shank body.

In Figs. 7 to 9 inclusive, I have shown the shoe shank as comprising only the shank wing 15 having prongs 16 at each end and 105 provided with a neck 17 by which said shank wing may be secured to an arch pad 5 beneath which, in most cases, a shank body of well known ordinary or standard construction is adapted to be located. This shank 110

wing may be attached to the arch pad by rivets 18 or their equivalent passing through holes 19 in the neck 17 and then through the pad.

5 In Fig. 10, I have shown a shank wing of similar construction, except that the holes 19 in the neck are eliminated and the free end of said neck is bent up and sharpened to provide a barb 20 to penetrate the arch 10 pad 5 and provide an additional point for embedment in the outer sole when the same is placed in position.

In practice the shoe shank may be attached to the inner sole by means of rivets 15 21 or their equivalent which pass through the shank body, as shown in Fig. 1, and if desired or the necessity arises the shank wing shown in Fig. 7 may be likewise secured directly to the inner sole with the resultant elimination of the arch pad.

As will be noted in Fig. 1 the shank underlies or engages the welt and inseam sewing so that this portion of the shoe will be reinforced because of the strains generally existing at this point. The prongs on the shank wing being embedded in the outer sole, said shank wing is prevented from sliding relative to the outer sole thereby adding the desired stiffness.

30 A shoe shank constructed in this manner not only provides for supporting the bottom

part of the arch of the shoe or the arch of the wearer's foot but also supports one of the sides thereof. This device will therefore retain the shoe in proper shape and in a great many cases will provide sufficient support for the arch of the wearer's foot to prevent or ease a fallen arch.

Of course I do not wish to be limited to the exact details of construction as herein shown as these may be varied within the limits of the appended claims without departing from the spirit of my invention.

Having thus fully described my invention, what I claim as new and useful is:—

45 1. In combination with a shoe, a shank body interposed between the inner and outer soles, a shank wing projecting from one side of said body and adapted to underlie the side of the shoe arch and means on the wing 50 for embedment in the outer sole.

2. In combination with a shoe, a shank body interposed between the inner and outer soles, shank wings projecting from opposite sides of the shank body and adapted to underlie the sides of the shoe arch and prongs at the ends of said wings for embedment in the outer sole.

55 In testimony whereof, I have hereunto affixed my signature.

CHARLES ZERGA.
